UNITED STATES PATENT OFFICE.

JOHN T. CAMPBELL, OF RICHMOND, INDIANA.

MAIL-BAG-TRANSFERRING MECHANISM.

1,273,575.

Specification of Letters Patent. Patented July 23, 1918.

Application filed November 3, 1917. Serial No. 200,146.

To all whom it may concern:

Be it known that I, JOHN T. CAMPBELL, a citizen of the United States, residing at Richmond, in the county of Wayne and State of Indiana, have invented certain new and useful Improvements in Mail-Bag-Transferring Mechanism, of which the following is a specification.

This invention relates generally to mail bag transferring mechanism, and has for its primary object to simplify and improve the construction and operation of devices of this character, as well as to increase their efficiency.

15 A further object of the invention is to provide a transferring device by the use of which mail pouches may be transferred from a stationary train to a moving car and from a moving car to a stationary holder with but small possibility of the bags or 20 their contents becoming damaged or destroyed.

Still further objects reside in providing a transferring mechanism of the type mentioned which shall be of extremely simple and inexpensive construction, which involves but a slight departure from the mechanisms now in use for the same purpose, which is wholly automatic in its interchanging operations, which requires no attention after once being set, which has its parts so constructed and arranged as to minimize the opportunity for wear or breakage, and which will prove highly practical and efficient in use.

With these objects in view, together with others which will appear as the description proceeds, the invention resides in the novel formation, combination, and arrangements 40 of parts, all as will be described more fully hereinafter, illustrated in the drawings, and particularly pointed out in the claims.

In the drawings:—

Figure 1 is a sectional plan view taken 45 through a conventional form of railway mail car, and illustrating the mechanism both upon the car and beside the track by the use of which the interchanging of mail bags is carried out,

50 Fig. 2 is a side elevation of a railway mail car equipped with a mechanism of my invention,

Fig. 3 is an elevation, parts broken away, of the stationary bag receiving device, and

Fig. 4 is a sectional view taken upon line 55 4—4 of Fig. 1.

Referring now more particularly to the drawings, 5 indicates a conventional form of railway mail car, having the vertically disposed posts 6 defining the edges of the 60 door therein. Projecting outwardly from the exterior of the car adjacent the edges of the doorway are bearings 7, the same being in horizontal alinement. These bearings support the extremities of the catcher arm 65 supporting bar 8, and the latter is adapted to be easily removed from the said supporting bearing. The catcher or grabber which is supported by the bar 8 is of the ordinary construction, and includes the outwardly 70 and forwardly extending arm 10 having a loop portion 11 at its juncture with the said bar, and within which bags received by the arm are adapted to rest. To hold the bags against becoming lost from the grabber 75 arm after once becoming engaged thereby, a lever 12 is pivoted as at 13 to the arm support, and a spring 14 normally holds the said lever across the open end of the loop 11. It is obvious, therefore, that when a 80 bag is engaged by the arm 10, the same will move inwardly and will snap past the lever 12, and the latter will hold the bag from becoming disengaged from the grabber arm. The grabber mechanism may be provided 85 with the usual operating hand grip 14', which is grasped by the mail clerk within the car to properly position and hold the catcher arm so as to engage a bag supported on a suitable crane beside the track. The 90 bar 8 and the grabber mechanism carried thereby may be readily disengaged from the supporting plates 7, so as to enable the same to be reversed upon the car.

Secured in spaced relation and in vertical 95 alinement to the car 5 and preferably to the vertical posts 6 defining the door opening are brackets 15. These brackets are adapted to rotatably support the ends of a detachable crane pintle or rod 16, which is 100 provided with right angularly disposed arms 17. The arms 17 are adapted to support between them a mail pouch for delivery to a station, and are of such length that the bag supported thereby will be held an ap- 105 preciable distance beyond the side of the mail car. This car crane is capable of swinging toward or away from the door way

and the side of the car, to facilitate the application of mail bags to the device, and may also be readily removed from the brackets upon the car and positioned upon either side 5 of the car or either side of the door way.

The mechanism which is to be arranged beside the track for the purpose of taking bags supported upon the car by the arms 17, includes a horizontally disposed supporting bar or rod 18, the latter being rigidly supported by the spaced posts 19. Mounted for sliding movement upon the bar or rod 18 is a sleeve 20, having a grabber arm 21 extending outwardly from one side 10 thereof. The grabber arm 21 is bent adjacent its juncture with the sleeve so as to provide a loop 22, similar to the loop 11 in the mail car grabber arm, for the purpose of receiving and retaining mail bags. To 15 securely hold the mail bags within the loop 22 and also to hold the sleeve 20 against sliding movement upon the support 18 is a lever 23, the latter being pivoted to one end of the sleeve as at 24. One end of this 20 lever, designated at 25, normally extends across the open end of the loop 22, while the short end 26 of the lever is adapted to engage the bar or support 18 to firmly hold the sleeve 20 against sliding movement 25 thereon. A spring 27 normally holds the lever in bag retaining and bar engaging position, but it is obvious that a bag forcibly moved inwardly of the grabber arm 21 will snap past the lever 25, thereby gaining access 30 to the loop 22, and at the same time disengaging the end 26 of the lever from the bar 18.

The sleeve 20 at its forward end is provided with a pin 28, disposed parallel to 40 the supporting bar 18. This pin is adapted to enter a suitable aperture in one of the posts 19, to hold the sleeve 20 against rotation and with the grabber arm 21 in proper operative position. When the sleeve 20 is 45 moved rearwardly upon the support 18 until the pin 28 is withdrawn from the aperture in the post, the weight of the arm 21 and a bag or bags held thereby will cause the sleeve to rotate so that the said grabber 50 arm will be disposed downwardly and in inoperative position.

In order that the violent rearward sliding movement of the sleeve 20 may be cushioned, the rod 18 at its rear end is 55 circled by an expansion spring 29, the said spring bearing at its rear end against one of the supporting posts for the said bar. A collar 30 is held by the forward end of the spring 29, and against which the rear 60 end of the sleeve 20 engages. It is obvious, therefore, that when the grabber arm 21 has delivered thereto a mail bag from a fast moving train, the rearward movement of the grabber mechanism will be gradually 65 checked by the spring mechanism.

As it is the purpose of the invention to provide for mail bags being taken from trains moving in either direction upon the tracks, two of the grabber arm mechanisms above described are provided, both being 70 of identical construction but facing and operating from different directions.

The crane beside the track for properly holding bags to be transferred to the moving car may be of conventional form, and 75 is illustrated in Fig. 4 of the drawings. This crane comprises a pair of spaced outwardly extending crane arms 31, supporting between them at their outer ends a bag indicated at 32, and are of such length as 80 to hold the bag in the path of travel of the grabber arm 10 upon the car when the said arm is swung outwardly to catching position.

When it is desired to cause the transfer 85 of mail bags from a car to a station beside the track, and vice versa, the crane upon the car is positioned in the brackets 15 in the rear of the grabber arm 10 therein. The bag to be delivered to the station beside 90 the track is then secured between the arms 17 of the car crane, whereupon the latter is swung outwardly, as shown in Fig. 1. The bag to be transferred from the stationary mechanism to the moving car is in a like 95 manner interposed between the arms 31 and the stationary crane. The sleeve 20 is then moved forwardly upon the arm 18, and is rotated so that the pin 28 thereon will enter the aperture in the post 19. By 100 so positioning the sleeve, the grabber arm 21 will be extended toward the track or in operative position, and the pin 28 will hold the sleeve 20 against rotation. As the mail car approaches the station, the clerk, by 105 means of the handle 14', swings the catcher arm 10 outwardly, so as to grab the bag 32 held by the crane arm 31. The bag held by the outwardly projecting arms 17 of the car crane will be engaged by the outwardly and 110 forwardly projecting arm 21, and the said bag will enter the loop portion 22 of the said catching mechanism. The inward movement of the bag will cause the lever 25 to open, permitting the bag to enter the 115 loop portion, and simultaneously with this opening movement of the lever, the catch arm 26 of the lever will release the sleeve 20. The sleeve will at once move rearwardly upon the support 18, and will be 120 checked in this movement by the spring 29 at the rear end of the support. The support 18 may be of any preferred length. The bag 32 will be engaged by the grabber arm 10 upon the crane, and, by means of the 125 lever 12, will be held against becoming lost therefrom.

From the foregoing it is obvious that I have provided a transferring mechanism for mail pouches which involves but a very 130

slight departure from mechanisms of a similar nature now in use, but which will greatly facilitate the interchange of mail bags. It will be impossible for the mail pouches being dropped from their grabber arm to become damaged or destroyed, and the bag delivered from the moving train does not touch the ground.

While the present is a disclosure of what is believed to be the preferred embodiment of the invention, it is to be understood that the invention is not limited thereto, but that various changes in the minor details of construction, proportion, and arrangement of parts may be resorted to if desired without departing from the spirit of the invention as defined by the appended claims.

I claim:—

1. In a mail transferring device, a horizontal rod, a sleeve slidably mounted on said rod, a grabber arm secured to said sleeve, a lever pivoted inwardly from its

ends to said sleeve, a spring for normally holding one end of said lever between said sleeve and said arm and for holding the opposite end of said lever frictionally engaged with said rod.

2. In a mail transferring device, a horizontal rod, a sleeve slidably mounted on said rod, an arm secured at one end to said sleeve and having a loop portion adjacent its juncture with the said sleeve, a lever pivoted inwardly from one end to said sleeve, a spring on said sleeve yieldably holding one end of said lever disposed across said loop portion, and the other end of said lever being frictionally engaged with said rod.

In testimony whereof I affix my signature in presence of two witnesses.

JOHN T. CAMPBELL.
